NAIL STRAIGHTENING MACHINE

George Delbert Hulbert, Los Angeles, Calif., assignor to Twentieth Century-Fox Film Corporation, Los Angeles, Calif., a corporation of New York

Application May 25, 1943, Serial No. 488,365

2 Claims. (Cl. 153—48)

1

This invention deals with a machine for straightening nails.

The machine to be described and claimed hereinafter has been designed for the purpose of salvaging nails. It is to be understood that the nails to be straightened by the machine must first be extracted and then fed to the machine in the manner to be later explained. The machine straightens the nails in a single operation and has been found to give satisfactory results on nails bent almost to an angle of ninety degrees. In practice, the nails are straightened cold.

In its preferred form the apparatus consists of a rotating, circular table carrying V-shaped slots or dies adapted to receive the crooked nails and bring them under a reciprocating shoe which is synchronized with the movement of the table to engage the nails in the slots and press them into a more or less straightened condition. A noteworthy feature of the shoe and die construction is the arrangement of wings or fins extending laterally and downwardly from the side of the shoe to form a V-shaped guide on the bottom of the shoe. These fins work in slots in the die and serve the purpose of forcing extremely crooked nails into the bottom of the V-shaped slot before the straightening force is applied. Another feature worthy of mentioning is the fact that the shoe and the die are so formed as to force the nail slightly beyond the straightened position when the shoe has reached the end of its pressure stroke. This is for the purpose of forcing the material in the nail to set slightly beyond the straightening point, thus allowing for any spring-back in the nail.

Accordingly, it becomes an object to provide a nail straightening machine wherein the nails are placed in a rotating table having nail receiving slots therein and a reciprocating plunger having a shoe on the end thereof is adapted to enter said slots and press the nails into a more or less straightened condition.

Another object of this invention is to provide a nail straightening machine wherein nails may be straightened by pressing them into a V-shaped die by means of a V-shaped shoe adapted to fit said die and wherein the shoe has lateral fins arranged to form a V-shaped guide extending beyond the bottom pressure point on the shoe.

A further object of the invention is to provide a machine for the purpose described, characterized by simplicity, durability, inexpensiveness, and one which may be operated by unskilled labor.

2

Other objects and advantages will become apparent as the description proceeds in conjunction with the drawings in which:

Figure 1 is a side elevation partly in section of the complete machine;

Figure 2 is an end elevation partly in section of the same;

Figure 3 is a side elevation of part of the super structure;

10 Figure 4 is a top plan view of the machine;

Figure 5 is an enlarged fragmentary view of the die showing crooked nails and straightened nails in place;

15 Figure 6 is an enlarged fragmentary view of the die and the shoe;

Figure 7 is a view of the shoe taken at right angles to Figure 6;

Figure 8 is an enlarged fragmentary view taken in the direction of the arrow 8 on Figure 4; and

20 Figure 9 is a magnified sectional view of the shoe and die showing them in place with a nail in a straightened position.

Briefly stated, the invention comprises a rotating table generally designated 11 and a reciprocating shoe generally designated 12. The table 11 carries a plurality of dies, or V-shaped slots designated 13, which are a part of the table and adapted to be rotated therewith and by means to be later described, synchronized with the movement of the shoe 12. The table 11 is suitably supported upon rollers 14, which are in turn carried upon a frame generally designated 15 and is journaled in the middle through bearings 16 and 17 adapted to rotatably receive a shaft 18 fixed to the center of the table. This structure will be seen to provide a rotatable support for the table 11 and at the same time furnish sufficient supporting means so that enough pressure can be brought to bear on the table to straighten the nails. No detailed construction of the frame will be given, since it may take a variety of forms such as a fabricated frame or a cast frame, either of which will be suitable for the purpose.

It will be observed, however, that one end of the frame extends above the table 11 and is provided with a crossbar 19. Suitably mounted on the crossbar 19 is a mechanism generally designated 20 which is for the purpose of reciprocating the shoe 12. As shown, this mechanism comprises a boxlike casing 21 into which is reciprocably fitted a cage 22. In the cage 22 there is a block 23 which is adapted to reciprocate therein. The block 23 in turn is mounted upon a pin 24, which pin is eccentrically mounted upon a disk 25, the disk 25 in turn being fixed to a shaft 26

that is driven by any suitable member such as a V pulley 27. Attached to the cage 22 is a shaft 28 which extends outwardly of the box 21 and carries on its lower end the shoe 12. As shown, the shoe 12 may be detachably mounted upon the lower end of the shaft 28 in any suitable manner, which in this case is shown as a small stub shaft 29 extending into the lower end of the shaft 28 and held therein by means of a set screw 30. Under this arrangement, the shoe may be changed for other sized shoes to accommodate the machine to different sizes of nails. Also, the dies would have to be changed to fit the shoe. The shoe also carried a flange 31 which is for the purpose of operating the intermittent movement of the table to be described later. The foregoing described mechanism is for the purpose of reciprocating the shoe 12. The entire unit just described is mounted upon the crossbar 19 in any suitable manner, which is shown as tongues 32 extending from the sides of the unit 20 that may be attached to the bar 19 in any suitable manner such as by bolts 33, or it may be welded in place if desired. For additional security, depending tongues 34 may be anchored to the side elements of the bar 19 by means of bolts 35. The means of mounting the unit 22 upon the crossbar 19 is unimportant in so far as the invention is concerned. The only requirement is that the mountings shall be sufficiently strong to withstand the pressure exerted when the shoe presses a nail in the die. The shaft 26 carrying the pulley 27 is further supported in a bearing 34 mounted upon the crossbar 19. From the foregoing structure, it will be seen that as the pulley 27 is rotated the shoe 12 is reciprocated.

As the shoe 12 is reciprocated it works a crank arm 36 on a pivot 37 mounted on the frame 15. The other end of the crank extends downwardly as indicated at 38 and carries a dog 39 pivotally mounted on the lower end. The end of the crank 36 is adapted to contact the flange 31 on the shoe 12 and for purposes of adjustment may be provided with a screw threaded bolt 40. As the shoe 12 moves upwardly, the arm 36 is forced upwardly with it and as the shoe moves downwardly in its cycle the arm 36, by force of gravity, will follow the movement of the shoe, thus applying a reciprocating movement to the crank arm 36. The arm 38 will move accordingly and the dog 39 will engage ratchet slots 41 in the periphery of the table 11. This will impart an intermittent movement to the table 11 and will bring successive slots 13 under the shoe 12. As a means of registering the slots under the shoe, I provide a spring detent arm 42 suitably mounted upon the frame and adapted to yieldingly engage the outer periphery of the table 11. The detent arm is formed with a tongue 43 adapted to fall into slots 44, which slots are spaced so as to register the slots 13 under the shoe 12. From the foregoing it will be seen that as the pulley 27 is rotated the shoe 12 is reciprocated and upon each reciprocation of the shoe the table 11 is intermittently advanced a distance sufficient to bring the next slot under the shoe, whereupon it is held by the above mentioned detent arrangement in registration with the shoe.

In operation an operator feeds the nails to the machine by placing each nail individually in the slots 13 on the table. He does this during the rest period of the intermittent movement of the table. As the table advances, the nails come under the shoe and are pressed in the bottom of the slots by the shoe 12. Sometimes, due to ex-

treme crookedness or rust, a nail is apt to stick in the bottom of the slots. To prevent this, I provide a depending arm 45 mounted upon an arm 46, extending from the frame 15. The arm as shown extends downwardly and is turned inwardly toward the dies 13 so that the inner end of the arm forms a sloping face 45' that engages the heads 47 of the nails as they lay in the bottom of the slot and by movement of the table raises the nails out of the bottom of the slot. The movement need be only a very slight movement, just sufficient to dislodge the nail from a wedged position.

As the nail advances around the table, it comes to an unloading position. For this purpose I provide a spring leaf 48 on the end of the arm 46. The end of the leaf 48 is adapted to slidably engage pins 49, mounted on the table 11 and spaced to correspond to the slots 13, and as the table moves the spring will drop off the pins 49 and will engage the inner ends of the nails 50 which lie in the bottom of the slots. The snapping movement of the spring will be sufficient to drive the nail from the slot and into a box 51 provided for the purpose. The operator may then reload the slots as they pass by the loading station.

Referring more particularly to the dies which are shown in enlarged form in Figures 5 and 6, it will be noted that the dies 13 are V-shaped slots 52 and that the shoe generally designated 12 has a V-shaped member 53 adapted to fit in the slot 52. On the side of the shoe I provide wings, or fins, 54 which terminate in a V-shaped formation 54' ahead of the bottom of the V-shaped shoe 53. The dies 13 are provided with openings 55 which extend transversely across the slot and are adapted to pass the fins 54. It is to be understood that in this instance I have shown two sets of fins 54 on each shoe but that more may be used if found necessary, and that the invention is not to be restricted to the fins that I have shown but that as many fins in as many locations as may be desired may be used. The nail 50 is placed in the slot, preferably with the bowed side up. The V-shaped portion 53 of the shoe 12 is formed on the lower edge with a convex surface, while the bottom of the shoe is concaved as indicated at 56 so that as the shoe presses the nail home in the slot the body of the nail is forced slightly beyond a straightened position to allow for any spring-back of the metal. The fins 54, since they extend below the point of the V on the shoe, will force the nail into the center of the slot so that a final pressure will be applied on the bottom of the V-shaped slot and the nail will not be allowed to slide in between the side of the shoe and the slot.

A machine of the character described has been found to straighten nails satisfactorily and has been operated with unskilled help to salvage nails that otherwise would have been lost.

I claim:

1. In a nail straightening machine, a rotary table having a plurality of dies adapted to receive bent nails with their pointed ends projecting out of the dies, a shoe adapted to reciprocate into and out of said dies, means operable by the movement of said shoe to intermittently rotate said table to register successive dies with said shoe so that pressure may be exerted upon nails in said dies by said shoe, and a member operable by the movement of said table to strike said projecting ends and drive the nails out of the dies.
2. In a nail straightening machine, a rotary

table having a plurality of dies therein adapted to receive bent nails having their heads and pointed ends projecting out of the dies, a shoe adapted to reciprocate into and out of said dies, means operable by the movement of said shoe to intermittently rotate said table so that said shoe may bring pressure to bear upon nails in successive dies in said table, a fixed sloping member adapted to engage the heads of said nails and dislodge them from the bottom of said dies, and a striking member operable by the movement of said table to strike said pointed ends and drive the nails out of the dies.
